(57) CLAIM

The ornamental design for a drinking vessel, as shown and described.

DESCRIPTION

FIG. 1 is a perspective view of a drinking vessel in accordance with the present invention showing the new design. FIG. 2 is a front view of the drinking vessel of FIG. 1, the back, left, and right side views of the design portion being identical thereto.
